UNITED STATES PATENT OFFICE.

WILLIAM T. BROWN, OF WINSTON, NORTH CAROLINA.

DESIGN FOR PLUG-TOBACCO.

SPECIFICATION forming part of Design No. 22,827, dated October 3, 1893.

Application filed September 8, 1893. Serial No. 485,113. Term of patent 7 years.

To all whom it may concern:

Be it known that I, WILLIAM T. BROWN, a citizen of the United States, residing at Winston, in the county of Forsyth and State of North Carolina, have invented and produced a new and original Design for Plug-Tobacco, of which the following is a specification, reference being had to the accompanying drawing, which forms a part of the same.

This invention relates to a design for a plug of tobacco; and it consists in the novel shape, configuration and ornamentation herein shown and claimed.

The figure of the accompanying drawing represents a plan or face view of a plug of tobacco having my design applied thereto.

The ornamental configuration constituting my design is impressed, or otherwise delineated upon the flat surface of an ordinary rectangular plug of tobacco.

The design embraces a Greek cross A hav-

ing suitable spaces or panels for any desired inscription and a central space, a' , dividing the said panels. In the corner spaces between the members of the cross, are represented the sprays or bunches of leaves, B, which are formed of three leaves, a , b , c , caught together at their stems, arranged adjacent to the angles between the members of the cross,—the three leaves being symmetrically arranged with their ends pointing outward, between the members of the cross, as shown.

What I claim, and desire to secure by Letters Patent, is—

The design for a plug of tobacco, substantially as herein shown and described.

WILLIAM T. BROWN.
